Primary Examiner — Susan Bennett Hattan

(74) Attorney, Agent, or Firm — Fulbright & Jaworski LLP

(57) **CLAIM**

The ornamental design for a cosmetic container, as shown and described.

DESCRIPTION

FIG. 1 is a top perspective view of my design;

FIG. 2 is a front view of my design;

FIG. 3 is a back view of my design;

FIG. 4 is a left side view of my design;

FIG. 5 is a right side view of my design; and,

FIG. 6 is a top view of my design.

The dashed lines in FIGS. 1-6 represent environmental structure and form no part of the claimed design. The bottom of the container, and all other surface(s) or portion(s) of the container not shown in the figures or otherwise described in the specification form no part of the claimed design.

1 Claim, 6 Drawing Sheets**US D691,474 S**
